BELL TYPE ANNEALING FURNACE

James H. Germany, Edgewood, Pa., assignor to
Westinghouse Electric & Manufacturing Company, East Pittsburgh, Pa., a corporation of Pennsylvania

Application October 7, 1939, Serial No. 298,461

2 Claims. (Cl. 266—5)

Bell furnaces are known, and generally comprise a refractory-metal inner hood placed about a charge, the hood being encased by an outer insulating bell with sufficient clearance space between the hood and the interior of the bell to permit the disposition of heating means therein. My invention relates generally to bell furnaces which are to be direct-fired with combustible fluid fuel, but which lend themselves to accurate control and distribution of the temperature within their heating chambers, the degree of accuracy of control being comparable to bell furnaces heated by electrical heating means in the form of sinuously-shaped resistor ribbons.

Direct-firing by gas in the space between the bell and hood is known, but has heretofore been employed only where relatively wide temperature discrepancies could be tolerated since it has been found extremely difficult to obtain accurate temperature control of bell-type furnaces employing direct gas-firing as a heating means. Accordingly, it is an object of my invention to provide a bell furnace construction adapted to be heated by direct gas-firing and which will have features enabling an accurate temperature control and distribution in the furnace.

In accordance with my invention, I provide a combustion space or chamber between the hood of the furnace and the encasing bell in which a mixture of a combustible gas and air is burned. However, to assure that there is absolutely no air or gas supplied to the combustion chamber other than that whose flow can be controlled, I completely seal the combustion space against infiltration or seepage of secondary air or gas.

It is, therefore, an object of my invention to provide a gas-fired bell-type furnace in which the burning of combustibles takes place freely in its combustion space, and which has its combustion space absolutely sealed against infiltration of unwanted air or gas which might tend to disturb the temperature balance by interfering with the controlled combustible gas and air proportions admitted to the combustion space.

An ancillary object of my invention is to provide a directly gas-fired bell-type furnace which is gas-tight at all places except the discharge flues for the products of combustion.

The importance of the features of my invention lies in the fact that, by controlling the amounts of the combustible fuel and air for combustion that are admitted to the space between the hood and the bell, complete temperature control of the heating process can be obtained, whether the furnace has a few burners each of

large capacity, or a multiplicity of burners individually supplying small amounts of heat, but in the aggregate enough to heat the furnace to the desired temperatures. As an example of a furnace employing my invention, and in which accurate temperature control and distribution may be obtained with efficient heating and long life, reference may be made to the application of C. E. Peck, Serial No. 298,456, filed concurrently herewith, and assigned to the Westinghouse Electric & Manufacturing Company.

A further object of my invention is to provide a bell-type furnace, direct-fired by gas, which has a hood provided with a horizontal skirt resting on the base of the furnace, and a bell having its bottom provided with a frame-like member of relatively narrow width which rests on the skirt of the hood so that the skirt may expand and contract with temperature changes; the furnace being provided with a tight seal preventing the infiltration, at the jointure of the bell and hood, of secondary air into the combustion space.

Other objects, features and innovations of my invention will be apparent from the following description thereof, taken in conjunction with the drawing, in which

Figure 1 is a vertical sectional view of the furnace including the features of my invention;

Fig. 2 is a plan view of a portion of the base frame-ring of the bell of the furnace;

Fig. 3 is a view, in section, of a detail of the lower seal of another form of bell furnace; and

Fig. 4 is an enlarged view, in section, of a burner mounted in the bell.

In many respects the bell-type furnace of my invention follows the general customary design in providing a foundation 2 upon which rests the base of the furnace, the base being indicated in its entirety by the reference numeral 4. The base, in general, comprises a structural steel framework, represented by the reference numeral 6, supported by the foundation, and underlying a base plate 8 which is, preferably, iron or steel of heavy stock, and therefore, gas-tight. A refractory and insulating hearth 10 is suitably supported on the base plate 8 and comprises a horizontal portion 12 completely covering the base plate and a plurality of spaced vertical piers 14 disposed inwardly of the periphery of the base, having embedded therein a heat-resistant skeleton framework 16 providing the charge-supporting part of the hearth.

A gas-tight hood, indicated in its entirety by the reference number 18, is disposed on the base 4 with its lower portion about and slightly larger

than the piers 14. The hood 18 generally comprises an upstanding portion 20 having a top 20' so that any charge resting on the charge-supporting framework 16 is completely encased by the hood. In the illustrated embodiment of my invention, the lowermost part of the hood is formed with an outwardly-directed, in this case, horizontal, skirt member 22 extending beyond the base and provided with a downwardly-extending flange 24 about its complete periphery which projects into a trough 26 welded gas-tight to the base plate 8 of the base, and also extending completely around the periphery of the base plate.

A bell, indicated in its entirety by the reference numeral 28, is adapted to be placed over the hood, and generally follows the contour of the upper portion of the hood but is somewhat larger, so as to provide a combustion space or chamber 30 between the two. The bell comprises an outer, gas-tight metal casing 32 completely enclosing it, and firebrick walls 34 having an inner refractory lining 36 defining part of the combustion chamber.

The construction of the furnace thus far described may be deemed to be somewhat conventional and in ordinary practice the bell is provided with an apertured bar or some equivalent device 38 by which it may be raised and lowered from and to its operating position about the hood. Positioning devices for mating the bell and base may also be employed.

Usually the charge inside the hood is heated while enveloped by a protective atmosphere which is either inert to the charge, or, in the case of nitriding or some other such process, may have a composition to carry out certain desired reactions therewith. Such a protective atmosphere may be admitted through an inlet pipe 40 and suitably circulated by a fan 42. An outlet pipe 44 for the protective gas may be provided extending through the base as an outlet for the atmosphere within the hood so that the heat-treatment chamber inside the hood may be purged when a heat treatment is started, and so that the atmosphere may be maintained clean and pure during the heat-treating process. The fan 42 for circulating the atmosphere within the hood may be connected to any suitable mechanism including a motor 46 driving a shaft 48 to which the fan is secured.

The pipes 40 and 44 are gas-tightly sealed to the base plate 8, as by welding, at the points where they pass through it and the shaft 48 may be provided with a gas-tight oil seal, such as shown and described in the application of Frederick R. J. Davis, Serial No. 221,719, filed July 28, 1938, and assigned to the Westinghouse Electric & Manufacturing Company, although any other seal may be employed which will assure a gas-tight joint between the shaft 38 and the base plate 8. In the same manner a thermocouple pipe 49 involved in the temperature control of the furnace passes through the base plate 8 and has a gas-tight joint with respect to it. Accordingly, the base plate 8 is gas-tight throughout its extent, and by providing a seal between the base plate and hood flange, the heat-treating chamber inside the hood is fully sealed.

For heating the furnace, a plurality of burners 50 may be arranged in vertically-spaced, horizontal rows, three such rows being shown in Fig. 1, and it may be observed that these burners are disposed in the lower part of the furnace. A plurality of flues 52 are provided in the top

5 of the bell through which the products of combustion may pass. There are, of course, a plurality of burners in each horizontal row, and also a plurality of flues, but in Fig. 1 only one in each row has been shown, the others having been omitted for the sake of clearness. To keep the burning gas from directly impinging on the hood the burners may be provided with turned-up snouts 54, or such snouts may be turned tangentially of the hood, or even omitted entirely with the burners directed tangentially of the hood if it be cylindrical.

One of the principal purposes of my invention is to gas-tightly seal the furnace at every place 15 where secondary or extraneous air or gas that might disturb combustion may possibly seep into the combustion space between the hood and the bell to the end that I may obtain in a direct-fired gas furnace a temperature distribution which is rigidly controllable. To this end the gas burners are secured gas-tight to the bell-casing 32, and I prefer to use a construction by which each burner has an outer pipe 56 provided with an outside flange plate 57 which can be secured 20 gas-tight, as by welding, to the outer casing 32 of the bell. Each burner is further provided with a gas-tight end plate 58 provided with an inlet pipe 60 gas tightly secured to the end plate 58 through which a controlled mixture of gas and air may be supplied to a burner block 61, it being understood that the entire structure is deliberately constructed so that no outside air can be inhaled by the burners. Consequently, the casing 32 can be considered air-tight except for the flues 52 which open into the atmosphere around the bell.

While I have described the burners as a premix type, it is obvious that any other suitable types of burners may be employed so long as the 25 openings in the bell in which the burners set are sealed gas-tight whereby only desired and controllable amounts of gas and air are admitted thereto, these being controlled in any suitable manner as, for example, by manipulation of valve-controlling mechanism 62, operable either 30 manually or automatically in response to temperatures within the furnace, or by some other means, as is well known to the art.

It has been customary in the construction of 35 directly gas-fired furnaces to terminate the outer metallic casing of the bell at approximately the horizontal skirt of the hood or some similar equivalent construction employed. This construction did not seal the combustion space of the furnace. While it might appear that in such a 40 structure only very limited amounts of air could seep into the combustion space through the crevices between the hood and the bottom of the bell, nevertheless such is not exactly the case due to the high chimney effects that are present, especially in high temperature furnaces. When 45 it is appreciated that the burning gases in the combustion space 30 may be at a temperature as high as 2000° F. and above, and are continually flowing upwardly to the flues 52, it is quite apparent that a considerable amount of outside air can be drawn into the combustion space even through small crevices at the jointure of the bottom of the bell and the hood. This possible condition is even more aggravated in bell furnaces 50 of better construction, such as shown, in which the bottom of the bell is provided with a bottom frame 63 of metal having inner slots 64 to provide for changes in dimension due to temperature variations, the slots extending from the

inner periphery about halfway to the outer periphery, and is further provided with additional appurtenances comprising a plurality of vertical gusset plates 66 secured to the inside of the casing 32 and the upper side of the bottom frame 63 for reenforcing the structure, and also a frame ring 68 secured to the bottom side of the frame 63 and of relatively narrow width compared thereto. The weight of the bell is transmitted to the bell supporting means, in this case, the base 4, through the ring 68, the purpose of the ring 68 being to permit "breathing" of the lower part of the hood so that it will not have a tendency to crystallize and crack through repeated expansions and contractions in the course of time.

An important feature of my invention is to completely seal this abutting joint between the lower part of the bell and the upper part of the hood or base, as the case may be, so that the combustion space 30 is completely sealed against any seepage or infiltration of any gases which might disturb the controlled proportions of the combustion mixture admitted through the burners 50. This leakage of secondary or unwanted air is very marked if the furnace is not sealed at the bottom due, primarily, to the chimney-like action caused by the difference in temperature between the gases inside the furnace and the air outside the furnace. To accomplish this, I gas-tightly secure to the casing 32 a downwardly extending flange 70 of metal completely encompassing the lower part of the bell, this flange 70 extending downwardly into the trough 26.

Accordingly, it may be observed that the combustion space 30 is completely confined within a metallic structure comprising the upper part of the hood 18 and the outer casing 32 of the bell, the only possible openings to the combustion space being at the flues 52 at the top of the bell, and the interspace between the flanges 24 and 70 at the bottom of the furnace. Since no air can filter or seep into the combustion space through the flues because of the outgoing combustion products, the space between the flanges 24 and 70 provides the only possible source of unwanted secondary air; this source, however, being sufficient to render ineffective attempts to control accurately the temperature distribution in the furnace.

In accordance with my invention, the space between the hood and bell casing is sealed gas-tight, and in the particular embodiment this is accomplished by filling the trough 26 with a liquid sealing medium 72 which might be oil, water, or even molten metal. I prefer not to use a granular substance such as sand or the like, since, as is well known, such materials are not impervious to the flow of gas therethrough.

My invention, therefore, provides a directly-fired bell furnace of the type described in which the combustion chamber or space is completely sealed against the admission of regulation-disrupting secondary air or gases which might affect the controlled combustion of the burning gases in the combustion space.

For extremely accurate temperature control, I prefer to make the hood and bell circular in horizontal cross-section. In other words, the hood and bell are preferably of cylindrical form, the advantages of this form briefly, residing in the fact that better distribution and flow of the burning gas are obtainable in a furnace having a cylindrical combustion space as compared to

other shapes offered in furnaces such as, for example, rectangular bell furnaces.

The operation of my furnace is, of course, obvious. The burners 50 supply regulatable amounts of gas and air to the combustion space 30 and since no other gases can seep into the combustion space, the heat produced is due only to the combustion of the desired amounts of gas and air flowing from the burners 50. Of course, it is obvious that if the admission of secondary air for combustion is deliberately wanted, its flow must also be regulatable if accurate temperature control and distribution are to obtain, so that it would still be necessary to use a furnace with a combustion space completely sealed except at its flues, the secondary air in such case being admitted through inlet means having appropriate flow-controlling means.

My invention enables me to construct a direct-fired gas furnace of the bell type for use where accurate temperature distribution or control is desired, as distinguished from a similar furnace usable for heat-treating only with considerable variations in temperature. In other words, I have provided a directly gas-fired bell furnace whose temperature can be controlled within limits much narrower than previously obtained.

By sealing the bottom of the furnace, the pressure conditions in the combustion chamber are definitely controllable, and are not disturbed by infiltration of secondary or extraneous air or gas which would not only disturb the pressure conditions, but also affect the combustion in the chamber, both in an unpredictable manner. These deleterious effects are even greater in structures where the bell is supported upon a relatively narrow member such as the ring 68. In practice, such a ring may be about one inch to one and a half inches in horizontal width, and about one inch thick for bells ranging from 8 to 14 feet in height with wall thicknesses ranging from 8 to 16 inches. It is quite apparent, therefore, that very short seepage paths of only one to one and a half inches in length are present all around the bottom of such a bell.

The provision of the sealing means such as I have shown not only eliminates the factors which hinder the application of directly gas-fired bell furnaces, or have rendered them unsuitable, for heat-treating processes requiring accurate temperature distribution and control, especially high-temperature processes, but also results in a more efficient furnace since the seal, by enclosing the bottom joint between the bell and hood, and providing a dead air space 74 as additional insulation, also decreases loss of heat by conduction and convection.

While I have shown my invention in a form which I now believe to be the best practical application thereof, it is obvious that other forms of embodiments and many equivalents are possible. Thus, for one example, the frames 63 might extend outward from the bell outer casing, a gas-tight weld being provided between the two. With such construction, the bell-sealing flange can be made integral with the frame 63 or gas-tightly secured thereto.

The structure of Fig. 3 differs from that of Fig. 1 in that the bell does not rest on the hood skirt but on a suitable understructure including I-beams 6'. The hood for this furnace has a skirt terminating in a flange 84 extending into the trough 80. To seal the space between the hood and the bell, a solid bottom frame 63' is gas-tightly secured to the bell casing 32, and is pro-

vided with a sealing flange 86 extending into the trough 80. The sealing means for the combustion space in this embodiment therefore comprises the liquid in the trough 80, the flanges 84 and 86, and the bell bottom frame 63'. If it be desired to seal the heating chamber under the hood, the base plate 8' may be provided with a depending flange 88 also dipping into the sealing liquid containing in the trough 80.

I claim as my invention:

1. A directly gas-fired furnace of the type described, comprising a base having a hearth adapted to support a charge to be heat-treated while enveloped by a protective atmosphere, said base comprising a metallic base plate; liquid-containing gas-tight trough means in gas-tight relation to said base plate; a gas-tight metallic-refractory inner hood adapted to be placed about the charge supported by said base, said hood cooperating with said base to form an enclosure for said charge, said hood having an outwardly-directed skirt, said skirt terminating in a peripheral flange depending into the sealing liquid in said trough means; means for delivering protective atmosphere to, and removing it from said enclosure; a removable, insulating, walled bell about said hood, said bell having an inner wall spaced from said hood to provide a combustion space, said bell having an outer air-tight metallic casing, said bell being provided with a plurality of distributed openings through its walls and casing, and with flue provisions in the upper portion thereof, said flue provisions being in communication with said combustion space for the discharge of gaseous products of combustion; 35

5 a plurality of gas burner means occupying said openings, for admitting controllable amounts of combustion-supporting gas and combustible fluid to said combustion space; said casing being provided with a downwardly-extending flange which is gas-tight with respect thereto; said casing flange depending into the sealing liquid in said trough means.

10 2. A directly gas-fired bell furnace of the type described, comprising a base adapted to support a charge to be heat-treated; a gas-tight metallic-refractory inner hood adapted to be placed about said charge and cooperating with said base to enclose said charge, said hood having a downwardly-directed peripheral hood flange; a removable, insulating, walled bell about said hood, said bell having an inner wall spaced from said hood to provide a combustion space, said bell being provided with flue provisions in communication with said combustion space for the discharge of gaseous products of combustion; a plurality of gas burner means for admitting controllable amounts of combustion-supporting gas and combustible gas directly into said combustion space; said bell being provided with a gas-tight outer casing, said casing having a downwardly-directed peripheral casing flange; and gas-tight sealing means for the bottom of said combustion space for making the bottom of said combustion space gas-tight, said sealing means comprising liquid-containing trough means into which said hood flange and said casing flange depend.

JAMES H. GERMANY.
